UNITED STATES PATENT OFFICE.

RUDOLF HASE, OF BERLIN, GERMANY, ASSIGNOR, BY MESNE ASSIGNMENTS, TO NAMLOOZE VENNOOTSCHAP FINANZIELE MAATSCHAPPIJ "DRIEBERGEN," OF AMSTERDAM, NETHERLANDS, A COMPANY OF THE NETHERLANDS.

RECORDING PHONOGRAPH.

Application filed February 18, 1921. Serial No. 446,201.

To all whom it may concern:

Be it known that I, RUDOLF HASE, a citizen of the German Republic, chief engineer, residing at Friedrichstrasse 24, Berlin, S. 5 W. 48, Germany, have invented new and useful Improvements in Recording Phonographs, of which the following is a specification.

The diaphragm of a telephonic sound-box 10 for dictating phonographs, telephonographs and like apparatus, is subject, as is well known, to various stresses; the continuous pull of the permanent magnet bends the diaphragm towards the poles; the pressure of 15 the stylus against the cylinder transmits through the attached lever mechanism an opposite pull on the diaphragm; the mechanical vibrations of the diaphragm resulting from the electric current ripples are 20 produced by a constantly alternating stress; and finally there is an inertia impulse which arises in consequence of the current impulse. The diaphragm cannot for long respond entirely elastically to the joint effect of all 25 these stresses and a permanent deformation occurs. This deformation gives rise to resonance effects in the vibrations of the diaphragm, which deteriorate the action of the sound-box until it is wholly unusable. The 30 subject of the present invention is a sound-box in which these faults are obviated by replacing the diaphragm by an armature mounted in front of the magnet poles, which is coupled in the usual way with the ends of 35 the inscribing lever mechanism. Such replacement of the diaphragm by an armature is accompanied with other striking advantages, dependent on the way the armature is mounted. In particular the armature 40 may be tuned to a definite natural frequency, by which means, when the dictating phonograph or telephonograph is used as a receiving apparatus in wireless telegraphy, it is possible to tune to a definite sender. 45 By adjustment of the armature, appropriate damping due to the magnetic field may be obtained. The air cushion between the poles and armature also has a damping effect. But this damping is dependent on 50 the distance of the armature from the poles, and, since the distance is in any case minute, it is very difficult to secure the proper adjustment. The invention therefore provides another means of obtaining good damping,

which consists in bringing to bear on the 55 armature more or less elastic buffers which are capable of adjustment. Such a buffer may be variously arranged in relation to the armature, according to the shape and mounting of the armature with respect to 60 the magnet poles.

In the drawings three examples of the invention are illustrated.

Figures 1 and 2 show one construction in 65 side and front views respectively.

Figures 3 and 4 are side elevation and plan from underneath respectively of a second construction, and

Figures 5 and 6 are views similar to Figures 3 and 4 of a third construction. 70

The powerful permanent magnet system 1 carries on its poles 2 the coils 3, through which the current ripples flow. The armature 4 is mounted in front of the poles 2 after the fashion of a beam upon two supports loaded with a single load. The two supports may be alike or different; it is essential that the armature, which is to be bent by the magnetic pull as its single load, shall be held at as small a distance from 80 the poles 2 as possible. By way of example Figure 2 shows the armature 4 pivotally mounted at one end at 5, while at the other end a more or less flexible tongue 6 is attached to it which bears against a stop 7. 85 This is to ensure that the armature shall not rock about one end, as happens in a relay or an electric bell; but shall only vibrate by bending, like a beam on two supports. The pivot 5 may be replaced by a stop 7 as at the 90 other end, but the pivot has the advantage that it suppresses twisting of the armature transversely to its length.

The pivot 5 is formed by a block 16 upon which the armature 4 is fastened between 95 two pointed screws 17. The stop 7 consists of a knife-edge or point 18, against which the end of the tongue 6 lies. In order that the armature 4 may be adjusted to a greater or less distance from the magnet poles 2 the 100 knife-edge or point 18 has an adjusting device, which may be constructed in any desired manner. For instance, as may be seen from Figure 2 the stem of the point 18 may be screwed more or less into the block 19, 105 by which means the distance between the armature 4 and the poles 2 is altered.

The inscribing lever mechanism is mount-

ed transversely to the armature 4, and consists in known manner of a lever 9 mounted on the block 8 which serves to take up the undulations of the phonograph cylinder. 5 The actual inscribing lever 10 is pivotally connected with this lever at 11. Upon one end is the stylus 12, while the other is engaged by a pull rod 13 which couples the inscribing lever 10 with the armature 4. The 10 coupling rod 13 is pivoted to the armature 4 at 14 as near as possible to the point of application of the magnetic pull. To support the whole sound-box the block 15 is attached to the slide by which the sound-box is traversed along the cylinder; this is not illustrated as its construction is known. 15

The action of the armature is such that in consequence of the magnetic pull it bends as a beam upon two supports with a single load. Since the magnetic force is overwhelmingly stronger than the pull of the suspended inscribing lever system the stress due to the inscribing lever can be neglected. The armature suffers bending by the magnetic force, and this bending varies in consequence of the current ripples in the current exciting the electromagnet, and is transmitted to the inscribing lever system so that the stylus inscribes the sounds received in the phonograph cylinder. To increase the sensitivity the stop 7 should be so adjusted that the distance of the armature 4 from the magnet poles 2 is as small as possible without causing danger of sticking. 30

35 In order to regulate the bending of the armature in a definite relation to the current ripples the tongue 6 may be designed of greater or less flexibility. For the reception of speaking currents it is desirable to use an armature having a natural frequency far above the frequencies of speech. At the same time the armature should be damped as well as possible in order still further to flatten the resonance curve. For the reception of wireless telegraph signals it is an advantage to tune the armature to a definite natural frequency by suitable design of the tongue 6, so that current oscillations of other frequencies may not occur and cause 40 disturbance, and only oscillations of the same frequency are received. This gives a means of tuning a telephonograph serving as a receiving apparatus to a definite sender, so that only the signals given by it are received. 45

50 Various means may be employed to tune the armature 4 to a definite frequency. It is desirable to design the sound-box from the outset for a certain range of frequencies, and to effect fine tuning within these limits by adjustment. To adapt the sound-box for frequencies beyond this range, the tongue 6 may be designed of different stiffness, say by altering its thickness or width, or the 55 knife-edge or point 18 of the stop 7 may be

replaced by a flat surface. Finer tuning may be obtained by adjustment of the stop 7 so as to bring the armature 4 more or less near the poles 2, the effect being that the damping by the magnetic field is altered. 70 Other known means of damping may also be employed as required, for instance mechanical damping by which the movements of the armature are directly damped. The natural frequency may also be varied by 75 lengthening or shortening the armature by lateral shifting of the stop 7, for which purpose the block 19 should be provided with an adjusting device for shifting it laterally. 80

In the construction illustrated in Figures 3 and 4 the armature 4 has a prolongation 20 extending beyond its support at the opposite end from the tongue 6. Where a pivot support is used this prolongation should be at the pivot end. A buffer 21 is 85 arranged to bear on this prolongation. This buffer comprises a foot or socket 22, in which the stem 23 of a cup 24 is adjustably mounted; for instance the stem may be threaded. In the cup is a soft block 25, which by suitable adjustment of the cup, can be made to bear gently against the prolongation 20. Such adjustment of the buffer causes damping in the sense that it suppresses the natural vibrations of the armature, while other 90 vibrations due to the current ripples are rendered aperiodic. 95

The buffer 21 may be arranged on the other side of the armature prolongation 20, so that it bears in the opposite direction 100 upon the armature, with however, substantially the same effect. The essence of the arrangement is the interposition of resilient material between any point on the armature and a fixed part, so as to damp the natural 105 oscillations of the armature. 100

Another construction of the buffer is shown in Figures 5 and 6. This is mounted upon a bridge 26 spanning the magnet and armature, and bears upon the back of the 110 armature. As before it consists of the stem 23, the cup 24, and the soft inlay 25. The socket 22 within which the stem 23 is adjustable is secured inside the bridge. 115

The same end may be attained by checking by the aid of a damping buffer not the armature itself but a part fixed to it. For instance the coupling rod 13 operating the inscribing lever system, instead of being linked to the armature, may be secured rigidly to 120 it by a screw 29, and may pass between cork cushions, as indicated at 28 in Figure 3. Such cushions may for instance be mounted on a bridge like 26. 125

What I claim is:

1. In sound recording apparatus the combination with a magnet core of windings to carry speaking current, a bar armature adjacent the poles of said magnet, a resilient tongue rigidly secured to said armature 130

ture and forming a prolongation thereof, supports, one bearing upon said armature and one upon said resilient tongue sustaining said armature against the attraction of said magnet, an inscribing lever mechanism and a connection between said lever mechanism and said armature.

2. In sound recording apparatus the combination with a magnet core of windings

10 to carry speaking current, a bar armature adjacent the poles of said magnet, a pivotal support at one end of said armature, a resilient tongue attached to the other end of said armature, an adjustable abutment for said tongue to support the armature against the magnetic pull, an inscribing lever mechanism and a connection between said lever mechanism and said bar armature.

3. In sound recording apparatus the combination with a magnet core of windings 20 to carry speaking current, a bar armature adjacent the poles of said magnet, a resilient tongue attached to and prolonging said armature, supports, one bearing upon said armature and one upon said resilient tongue sustaining said armature against the attraction of said magnet, a buffer bearing upon said armature to damp its oscillations, an inscribing lever mechanism and a connection between said lever mechanism and said armature.

4. In sound recording apparatus the combination with a magnet core of windings

to carry speaking current, a bar armature adjacent the poles of said magnet, a pivotal support at one end of said armature, a resilient tongue attached to the other end of said armature, an abutment for said tongue to support the armature against the magnetic pull, an inscribing lever mechanism and a connection between said lever mechanism and said bar armature.

5. In sound recording apparatus the combination with a magnet core of windings 35 to carry speaking current, an armature adjacent to the poles of said magnet, means for tuning said armature to a particular frequency of oscillation, an inscribing lever mechanism, and a connection between said lever mechanism and said bar armature 40 adjacent to the effective point of application of the magnetic pull.

6. In a sound recording apparatus the combination with a magnet core of windings 45 to carry speaking current, a bar armature adjacent the poles of said magnet, a resilient tongue secured directly to said armature, supports bearing respectively said armature and said tongue and sustaining said armature against the attraction of said magnet, 50 a pivoted stylus carrying lever, and a link connecting said lever directly with said armature.

In testimony whereof I have signed my name to this specification.

RUDOLF HASE.
